(57) **CLAIM**

The ornamental design for a ratcheting driver, as shown and described.

DESCRIPTION

FIG. 1 is a perspective view of a ratcheting driver showing our new design when the ratchet is in its extended disposi-

tion, and including a driver bit shown in dotted lines as being inserted in the end of the ratcheting driver opposite the ratchet;

FIG. 2 is a perspective view of the ratcheting driver of FIG. 1 showing our new design when the ratchet is in its retracted disposition, and including a driver bit shown in dotted lines as being inserted in the end of the ratcheting driver opposite the ratchet;

FIG. 3 is a top plan view of the design of our ratcheting driver when the ratchet is in the disposition shown in FIG. 1, and including a driver bit shown in dotted lines as being inserted in the end of the ratcheting driver opposite the ratchet;

FIG. 4 is a right side elevational view of the design of our ratcheting driver when the ratchet is in the disposition shown in FIG. 2, the left side elevational view being a mirror image thereof;

FIG. 5 is a right side elevational view of the design of our ratcheting driver when the ratchet is in the disposition shown in FIG. 1, the left side elevational view being a mirror image thereof;

FIG. 6 is a front elevational view of the design of our ratcheting driver;

FIG. 7 is a rear elevational view of the design of our ratcheting driver; and,

FIG. 8 is a bottom plan view of the design of our ratcheting driver when the ratchet in the disposition shown in FIG. 3.

The broken lines shown in FIGS. 1-3 are for illustrative purposes only and form no part of the claimed design.
